YOST ELECTRIC MANUFACTURING COMPANY, OF TOLEDO, OHIO, A CORPORATION
OF OHIO.

CONNECTING DEVICE.

1,086,588.

Specification of Letters Patent. Patented Feb. 10, 1914.

Application filed January 6, 1913. Serial No. 740,457.

To all whom it may concern:

Be it known that we, FRANK H. CHAPMAN and OWEN E. KENNEY, citizens of the United States, and residents of Toledo, in the county of Lucas and State of Ohio, have invented a certain new and useful Connecting Device; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to connecting devices for electric circuits, but is not restricted to such use as it may be used in any connection for which it may be adapted or appropriate.

The object of our invention is to simplify and improve upon the construction of connecting devices of this character, whereby to enhance the practicability and commercial value thereof.

The invention is fully described in the following specification, and while, in its broader aspect, it is capable of embodiment in numerous forms, a preferred embodiment thereof is illustrated in the accompanying drawings, in which—

Figure 1 is a side elevation of a device embodying the invention, with the plug member in central longitudinal section and the socket member in partial section, and with the members in released positions. Fig. 2 is a similar view thereof with the members in engaged positions. Fig. 3 is a cross-section on the line $x-x$ in Fig. 2; and Fig. 4 is a side elevation of the plug member.

Referring to the drawings, 1 designates a socket member of customary or any suitable form having the central contact 2 and the threaded or spirally grooved socket lining 3. The plug member of the connection comprises the body part 4, which is provided with a longitudinally extending socket 5 opening without the outer or free end thereof, and the plunger 6, which is mounted for free reciprocatory movements within the socket 5. One or more coiled compression springs 7 are disposed between the base of the plug socket 5 and the plunger to cause

the plunger to normally project without the end of such socket, as shown in Fig. 1.

The plunger 6, in the present instance, has longitudinally-extending conductor-bars or strips 8 and 9 secured thereto by screws 10, or in any other suitable manner, and attached at their inner end portions to lead-in wires 11 and 12, respectively, which wires enter the socket 5 through a restricted opening 13 in the plug part 4. The conductor-bar 8 has its outer end bent across the outer end of the plunger in position to engage the socket contact 2 when the plug is inserted into the socket member, as shown in Fig. 1. The other conductor-bar 9, has its forward or outer end portion offset relative to its inner end portion transversely of the plunger, as at 9', and inwardly tapered at its inner end to adapt it to coact with a contact block 14 to force it outward when the plunger is moved inward relative to the plug from its normally extended position, as shown in Fig. 2.

The block 14 is of segmental form and works in a slot 15 disposed transversely of the plug through a side wall of the socket 5 in register with the conductor-bar 9. The radial or inward and outward movements of the block are limited by pins 16, which extend across the slot 15 through slots 17 in the block. The outer edge of the block 14 is complementary to the threads or spiral grooves of the socket lining 3 to adapt it to interengage therewith when projected from the plug, as shown in Figs. 2 and 4. The longitudinal movements of the plunger 6 relative to the plug part 4 are limited by a pin 18 projecting from the plunger and working in a registering slot 19 in said part.

To firmly engage and make electrical connection between a plug embodying the invention and a socket it is only necessary to insert the plug into the socket until the plug contact 8 engages the socket contact 2, whereupon a continued inward movement of the plug forces the plunger therein against the influence of the springs 7 and effects an outward movement of the contact block 14 into engagement with the threaded interior of the socket. The plug is now given a slight turn in a clockwise direction within the socket to firmly secure the parts together. This manner of connecting the plug and socket is found in practice to be very

efficient in its action, and is also simple and inexpensive of construction, and admirably adapted as a quick connecting device for electric light circuits and the like.

5 It is to be understood that the invention is not limited to any specific construction or arrangement of the parts except in so far as such limitations are specified in the claim.

Having thus described our invention,
10 what we claim as new, and desire to secure
by Letters Patent, is,—

15 A plug having a socketed body part with
an opening in its socket wall, an arcuate
block carried by the body part within said
opening for radial movements relative
thereto, said block being spirally disposed
relative to the body part and forming a
segment of a screw thread, a plunger work-
ing in said socket axially thereof and nor-
20 mally standing in outwardly projected rela-

tion thereto, said plunger having a longi-
tudinally extending recess in one side, a
strip of hard material secured in said recess
with its opposite end portion radially offset
relative to the plunger and connected by a
25 tapered portion, said strip being in register
with said block, and the tapered and outer
end portions thereof being adapted to coact
with the block to force it outward and to
hold it in such position when the plunger is
30 moved inward from normal position, sub-
stantially as described.

In testimony whereof, we have hereunto
signed our names to this specification in the
presence of two subscribing witnesses.

FRANK H. CHAPMAN.
OWEN E. KENNEY.
